UNITED STATES PATENT OFFICE

2,399,950

RAILWAY FREIGHT CAR

Carleton K. Steins, Merion, Pa., assignor to The Pennsylvania Railroad Company, Philadelphia, Pa., a corporation of Pennsylvania

Application July 13, 1943, Serial No. 494,470

12 Claims. (CL 105—329)

This invention relates to railway cars used for shipments subject to damage by freezing and is concerned with the heating of such cars.

The chief aim of my invention is to enable conversion of freight cars particularly of the bunker refrigerator type for use in transportation, during the winter, of perishable commodities such as vegetables and fruits which must be kept at a temperature above freezing for protection against spoilage, and yet enable the car to be employed in its full capacity when heating is not required.

These desiderata are attained in practice as hereinafter more fully set forth through provision of compartments for removable heaters, of which the component parts are collapsible and storable within hollows in the car walls so as to be flush with the inner surfaces of such walls when not in use.

In connection with a freight car having the above attributes it is a further aim of my invention to provide for ready access to the heater compartments from the exterior of the car so that the heaters may be removed or refueled when necessary, without entailing disturbance of the lading.

Other objects and attendant advantages will appear from the following description of the attached drawings, wherein

Fig. 1 is a view partly in top plan and partly in horizontal section of a top bunker refrigerator car conveniently embodying the present improvements.

Fig. 2 is a cross section of the car taken as indicated by the angled arrows II—II in Figs. 1 and 3 and drawn to a larger scale.

Fig. 3 shows the car in vertical longitudinal section.

Fig. 4 is a fragmentary horizontal sectional view taken as indicated by the angled arrows IV—IV in Fig. 2, and also drawn to a larger scale.

Figs. 5 and 6 are fragmentary vertical sections taken as respectively indicated by the angled arrows V—V and VI—VI in Fig. 4, the section of Fig. 5 being also indicated by the angled arrows V—V in Fig. 6.

Fig. 7 is a fragmentary cross sectional view taken as indicated by the angled arrows VII—VII in Fig. 4.

Fig. 8 is a fragmentary vertical sectional view taken as indicated by the angled arrows VIII—VIII in Figs. 4 and 7.

Fig. 9 is a fragmentary detail view in elevation looking as indicated by the angled arrows IX—IX in Fig. 8.

Fig. 10 is a fragmentary sectional view taken as indicated by the angled arrows X—X in Fig. 9.

Fig. 11 is a fragmentary sectional view corresponding to Fig. 4 and showing more clearly structural details at the region of connection of one of the wall components of a heater compartment with a contiguous side wall of the car; and

Fig. 12 is a fragmentary view in side elevation of the car looking as indicated by the angled arrows XII—XII in Fig. 1.

The car chosen for convenience of illustrating my invention is of the type commonly known as a top bunker refrigerator car having metallically reinforced hollow side walls S, S₁, end walls E, E₁, a roof R, a true floor or bottom F, and a false floor F₁ which latter is elevated from said true floor and formed by laterally-spaced longitudinally-extending slots or boards. The lading space within the car is reached through doors D, D₁ respectively at the centers of the side walls S, S₁, see Figs. 1 and 3. For the purposes of heat conservation, the walls S, S₁, E, E₁, roof R and true floor F are packed with suitable insulation I as conventionally shown. Also after usual practice, the car is provided along each side and directly beneath the roof with serially-arranged ice bunkers B, B₁ which are changeable from above through hatches H, H₁ in the roof R upon removal of the covers indicated at C, C₁. Under-reaching the bunkers B, B₁ with provision of clearances all around them are trays T, T₁. This construction, it will be seen, results in the formation of air flues A, A₁ which respectively extend upward of the side walls S, S₁ and laterally inward beneath the roof R and which terminate in a longitudinal slat-like port P that opens into the lading space within the car centrally of the top of the latter. During refrigeration when ice is used in the bunkers B, B₁, the chilled air will circulate in divided paths within the car reversely to the directions indicated by the arrows in Fig. 2 in a manner which is well known in the art and which need not therefore be elaborated upon here.

In order to convert a refrigerator car such as briefly described above for winter use, in accordance with my invention, I provide, preferably in opposite corners thereof, comparatively small low heater compartments 10, 10' for the accommodation of individual heaters 11 which may be of the oil, charcoal or other fuel burning types, and which are removably secured to the car floor F as best shown in Figs. 5 and 6, by wing bolts 12. Since the compartments 10 and 10' are identical 55 both as regards their construction and the ap-

purtenances associated with them, the immediately following description of one of them will hold for the other also. As shown, the heater compartment 10 is formed in part by the side wall S, one end wall E and the floor of the car, while the other two side wall components 13, 14 and top component 15 thereof are separately formed, being constructed from asbestos board panels or the like set into angle iron frames and covered with sheet metal as best seen in Figs. 4 and 6. The side wall component 13, it will be observed, is hinged at 16 to one of the supporting studs 17 of the inner paneling of the car wall E. The top component 15 is likewise hingedly connected to the car wall E at 18. From Figs. 5 and 6 it will be further noted that the car wall E is recessed at 19 to receive the top component 15 when the latter is swung upward as indicated in dot-and-dash lines, in which position it is releasably securable by means later described. The other or front wall component 14 of the compartment 10 has the frame angle bars 20 along one of its vertical edges removably engaged in a hooked channel strip 21 affixed to the car wall S, see Figs. 4, 7 and 11, with its opposite edge abutted by the swinging end of the side component 13 and its top edge abutted by the swinging edge of the top component 15. At the regions of mutual abutment the components 13—15 are detachably connected by releasable securing devices 22, 22a and 22b (Figs. 7 and 8) which are all of identical construction. Thus, for example, the device 22 illustrated in detail in Figs. 9 and 10 for connecting the side and top components 14 and 15 comprises a link element 23 with a pivot pin 25 whereof the ends are slidably engaged in pockets 26 at opposite sides of a cut-out 27 in the metal sheeting at one face of the front wall component 14. To the edge flange 28 of the top component 15 is affixed, in spaced relation, a pair of eyes 29 between which the link element 23 is received, and through which eyes and said element a cotter pin 30 is passed, said pin being attached by a chain 31 to said top component for assurance against being lost when it is withdrawn. As shown in Figs. 4 and 6, the inner lining or paneling of the car is also omitted below the recess 19 and an inwardly dished panel 32 of sheet metal there substituted. In dismantling the heater compartment 10, the cotter pins 30 and 30a of the securing devices 22 and 22a (Figs. 4, 9 and 10) are withdrawn with incidental dropping of the link elements 23, 23a into the confines of the cut-outs 27 and 27a in the side components 14 and 13, as shown in dot-and-dash lines in Fig. 10; whereupon the top component 15 is swung upward about its hinges 18 into the recess 19 therefor in the car wall E, as indicated in dot-and-dash lines in Fig. 6, and made fast by passing the cotter pin 30 through the eyes 29 and a link 33 (Figs. 5 and 6) similar to the link 23 of the securing device 22, pivoted to a bracket 34 on the car wall E immediately above the top edge of the recess 19. With this accomplished, the cotter pins 30b of the securing devices 22b are withdrawn to disconnect the front wall component 14 of the compartment 10 from the component 13. Thereupon the component 14 is swung outwardly slightly for release of its opposite edge 28 from the channel strip 21, and after being thus freed, is placed into the hollow of the panel 32 in the car wall E. Finally, the side wall component 13 of the heater compartment 10 is swung inwardly about its hinges 16 into the recess 19 against the component 14, as also indicated in dot-and-dash

lines in Figs. 4 and 6, and secured by sliding latch bolts 35 (Fig. 4) at its swinging edge into apertures 36 in a lining plate 37 of the car wall S. To facilitate manipulation during dismantling or setting up of the compartment 10, the side component 14 is provided as shown in Figs. 4 and 7 with hand holes 38. As a consequence of the described construction, it will be apparent that when the compartment 10 is collapsed (after removal of the heater 11 of course) its components form flush continuations of the inner face of the car wall E so that the full lading space in the car is available for freight when heating is not required or when the car is being refrigerated in the usual way.

In order that access may be had to the compartment 10 from the exterior for the purposes of refueling the heater or removing and replacing it, an opening 40 is formed in the side wall S of the car, said opening being fitted with a door 41 (Figs. 4, 5 and 12) which is hung on hinges 42 so that it may be swung upwardly as indicated by the curved arrow a in Fig. 5. Centrally of its bottom edge, the door 41 is provided with an eye 43, which, when said door is opened, is engageable with a keeper hook 44 (Fig. 5) pivotally connected to the side wall 1 of the car at 45. The door 41 is securable in closed position by a pin 46 passed through the eye 43 and a registering eye 47 on the side wall S of the car immediately below the door opening 40 as also shown in Fig. 5.

As instanced in Figs. 2 and 5 shutters 56 preferably formed from sheet metal are hinged at 57 to the walls S of the car so that they can be swung down over the openings 50, as indicated in dot-and-dash lines, when the heater compartments are collapsed, being securable in closed position by keepers 58 on the inner thicknesses 61 of the car walls S adjacent the lower edges of said openings. When the heater compartments 10 are in use, the shutters 56 are securable in open position by keepers 58 on the top or cover components of said compartments, as shown in full lines in Figs. 2 and 5.

With the compartments 10, 10' set up and the heaters 11 in them functioning, the air circulation within the car will be divided as indicated by the arrows in Fig. 2. That is to say, the air streams respectively warmed by the heaters 11 will pass by way of the lateral opening 50 from the tops of the corresponding compartments 10, 10' into and upwardly of the vertical portions of the flues A, A' in the contiguous side walls S, S' of the car, thence laterally in the respectively connecting horizontal portions of said flues, meeting at the slot-like port P and flowing through the latter into the top of the lading space at the center. Upon entering the lading space, the flow will dissipate and in so doing pass through and about the stored freight, finally finding its way through the interstices of the false floor F' to the horizontal passage beneath the latter whence it will again divide, part thereof returning into the bottom of one compartment 10 for reheating and the other part thereof into the bottom of the other compartment 10', the circulation being thus laterally of the car and maintained solely by convection.

While for the purposes of exemplification herein I have shown and described my invention with reference to a top bunker ice refrigerator car, it is to be understood that the same may be embodied through suitable modifications within the scope of the appended claims to other types of refrigerator cars or even to box cars of the ordinary kinds when heating is desired.

Having thus described my invention, I claim:

1. A railway car having within it a compartment for a removable heater, said compartment being formed in part by two meeting walls of the car and in part by a top component and two supplemental side wall components; means connecting said top component and one of said supplemental side wall components to one of said car walls with capacity for being folded thereagainst when the use of the compartment is not desired and the other side wall component being detachable and arranged to be accommodated behind the first side wall component when the latter is folded out of the way; and a door opening in one of the walls of the car by way of which access is had to the compartment from the exterior of the car.

2. The invention set forth in claim 1, in which the compartment is formed in part by a side wall, a contiguous end wall and the floor of the car.

3. The invention set forth in claim 1, in which the compartment is formed in part by a side wall, a contiguous end wall and the floor of the car, and in which the access opening is located in the side wall of the car.

4. The invention set forth in claim 1, in which the car wall to which the supplemental wall components are connected is recessed for reception of said components in flush relation with the inner surface of said wall.

5. The invention set forth in claim 1, in which the compartment is formed in part by a side wall, a contiguous end wall and the floor of the car; and in which said certain supplemental components are connected to said end wall of the car.

6. The invention set forth in claim 1, in which the compartment is formed in part by a side wall, a contiguous end wall and the floor of the car; in which the access opening is located in the side wall of the car; in which said certain supplemental components are connected to said end wall of the car; and in which said end wall is recessed to receive such components.

7. A railway car having within it a compart-

ment for a removable heater, said compartment being formed in part by a side wall, a contiguous end wall and the floor of the car and in part by supplemental side walls and a top component, one of the supplemental side components and the top component being hingedly connected to the end wall of the car with capacity to be swung into a recess in said end wall when the use of the compartment is not desired, and the other supplemental side component being connected to said one side component and the top component with capacity to be detached and placed in said recess behind said one side component.

8. The invention set forth in claim 7, in which the heater compartment is accessible from the exterior through a door opening in the side wall of the car.

9. A railway car having within it in one corner a relatively low boxlike compartment for a heater defined in part by a side wall, a contiguous end wall and the floor of the car, said compartment being accessible from the exterior through a door opening in one of said car walls, and being in communication at the bottom with the lading space of the car; and a hot air flow flue in communication with the top of said compartment and extending up through one of the car walls to a level adjacent the car roof.

10. The invention set forth in claim 9, in which the flue extends inwardly beneath the car roof and terminates adjacent the longitudinal center of the latter.

11. The invention set forth in claim 9, in which the access door to the compartment has a hollow constituting a portion of the flue.

12. The invention set forth in claim 9, in which the compartment is collapsible; in which the flue communicates with the compartment through a lateral opening in the side wall of the car; and in which a retractable cover hinged to said car wall serves as a closure for said lateral opening when said compartment is collapsed.
